United States Patent Office

Des. 183,657
Patented Oct. 7, 1958

183,657

AIRPLANE

Clarence L. Johnson, Encino, and William H. Statler,
Northridge, Calif., assignors to Lockheed Aircraft Cor-
poration, Burbank, Calif.

Application March 5, 1957, Serial No. 45,112

Term of patent 14 years

(Cl. D71—1)

Figure 1 is a perspective view of an airplane showing our new design;

Figure 2 is a front elevational view thereof;

Figure 3 is a top plan view thereof; and

Figure 4 is a side elevational view thereof.

The essential features of the design reside in the portions shown in full lines.

We claim:

The ornamental design for an airplane, substantially as shown and described.
